WILLIAM JAMES DRAY, OF NEW YORK, N. Y.

GRATE-CLEANING APPLIANCE.

Application filed August 20, 1920. Serial No. 404,861.

To all whom it may concern:

Be it known that I, WILLIAM JAMES DRAY, a resident of the borough of Manhattan, in the county, city, and State of New York, have 5 invented certain new and useful Improvements in Grate-Cleaning Appliances, of which the following is a specification.

The present invention has reference to means for keeping the grate-bars of a furnace clear of ashes, clinkers, and scoriacaceous matter that would clog the interstices there-between and consequently prevent the fuel from being properly consumed. It is particularly applicable to boiler furnaces of the 15 marine type, though it may be used with equal advantage in furnaces of stationary boilers or steam-generators.

An important object of the invention is to provide an appliance of the genus referred 20 to, that can be adjusted as a unit relatively to the grate to be cleaned, whether at the initial erection of the structure, or subsequently whenever the effectiveness thereof becomes impaired through continuous usage.

25 A further object is the provision of an appliance of the class mentioned the adjustment or re-adjustment whereof can be effected with convenience and sufficient rapidity, by an ordinary furnace attendant, without 30 using tools of any sort or calling anybody else to his assistance.

Another object is to produce an appliance of the character set forth carrying its own instrumentalities for adjusting and manipulating it, and thus affording a construction 35 which is complete in itself, and for that reason may be termed self-contained.

Still another object is the production of an 40 appliance of the nature described wherein the operating means can be utilized as a lock for maintaining the parts in a given position, and may also be employed in conjunction with some of the adjusting media to liberate the appliance from an abnormal condition.

45 Other objects of the invention will in part be obvious and in part be brought out more fully in the detailed description hereinafter contained.

The invention consists in the novel features 50 of construction, parts, combinations and sub-combinations of elements herein specified with reference to the accompanying drawings, and recited in the claims hereto appended.

55 In the said drawings,—

Figure I is a top plan view, partly broken and partly in section, representing a practical embodiment of the invention, applied to a marine boiler furnace;

Fig. II is a longitudinal section of the same construction, the parts being also partly broken as in the preceding figure;

Fig. III is a front end elevation, showing the lower half of the boiler shell, the furnace open with the grate-bars thereof in section, and the appliance operatively positioned, parts thereof being omitted; and

Fig. IV is a vertical transverse section on the irregular line IV—IV of Fig. II, looking in the direction pointed out by the arrows.

Referring now in detail to the drawings, the reference letter A designates a furnace flue of well-known construction, such as is 75 ordinarily employed for water-boilers or steam-generators of the type aforementioned. As usual, a front head B and an outer shell C surround this flue. The front end of the latter terminates with an extension D, of the 80 furnace containing a dead plate E, and at the rear end is a bridge wall F. The body of the flue may be formed with corrugations, as indicated at G.

85 Centrally mounted inside the said flue A, is a grate or series of grates, composed of parallel bars H, extending in longitudinal direction from the plate E to the wall F. If two or more grates are used, they are placed end to end in a same horizontal plane, substantially as represented in Figs. I and II. The several grate-bars H are arranged so as to bear at their opposite ends upon supporting-bars I, set across the interior of the flue and secured to the sides thereof at their respective extremities. As shown, these grate-bars may be formed with heads J, which serve to keep them at suitable intervals apart.

2
on the said supporting-bars, though they admit of being held adjoining one another thereon in various other ways.

Other parts pertaining to the furnace, its flue and grates, are omitted as having no particular bearing on the invention herein disclosed. With regard to the known parts above named, it is understood that they are devoid of novelty, considered by themselves, 10 and therefore will be claimed only as companion elements in the diverse combinations or sub-combinations set forth.

A vertically adjustable trackway is provided within the furnace flue A, directly below the grates H, and the same extends also forwardly at the same level into the extension D. Preferably and as shown, this trackway is composed of a pair of rails 1 and 2, that are parallel to the sides of the 15 flue and are united at their opposite extremities by transversely disposed rods 3 and 4 forming therewith a frame-like structure.

The trackway aforesaid rests at the front 25 and rear ends, respectively, upon brackets 7 and 8, or other terminal supports, adapted to receive and engage the cross rods 3 and 4. The several brackets may consist of sections of bar metal, set vertically within the extension D of the furnace in front, and the flue A in rear. The front brackets 7 are preferably bent inwardly and downwardly at their lower ends, as indicated by the reference numeral 9, and outwardly and 30 upwardly at their upper ends, as denoted by 10. These bends it will be noted, leave straight portions in the brackets 7 to support the trackway, and further supply appropriate bearing parts against opposite 35 points of the extension D, wherewith to fasten them in place. The rear brackets 8, on the other hand, may bear edgewise against the wall, F, and be secured at their lower extremities by bent portions 11 thereof, conforming to the incline of the bottom 40 part of the flue, as clearly seen in Fig. II.

Obliquely disposed notches 12 are provided in both the front and rear terminal brackets 7 and 8. These notches, it will be 50 observed, have downwardly extended parts adapted to receive the rods 3 and 4 of the trackway, and upwardly directed portions serving to hold the rods against displacement therein. Consequently, the said notches 55 constitute effective retainers and stepped supports for the said rods and the rails united thereby. A set or series of superposed notches 12 is cut into each one of the brackets, so that the trackway may be mounted 60 at different heights and inclines on the same.

Arranged to ride back and forth upon the rails 1 and 2, is a truck or carrier comprising two pairs of wheels 15 and 16, respectively secured to the ends of axles 17 and 18. As 65 appears in section in Fig. IV, these axles

constitute the extremities of squared members 19 and 20, which are connected together by longitudinally extending bars 21 and 22, see also Fig. II. These several parts compose the truck, which is intended for reciprocal travel under the grate or series of grates H, previously mentioned.

By preference, the above described truck is made somewhat longer than either of the grates shown in the drawings. In fact, it is 75 the intention to have a single truck of sufficient length to extend partly under the plural grates, irrespective of the number thereof in any series that may be used. The purpose of the truck, as plainly represented 80 is to carry rows of elongated teeth or raking elements, as 24 and 25, adapted to pass between the bars of all of the grates, whatever may be their number. The raking elements are secured at their lower ends to 85 the members 19 and 20, before referred to, and are upwardly directed therefrom so that their upper ends project slightly above the grate-bars, with enough clearance on each 90 side to avoid rubbing against the latter, as the said elements pass along the same when the truck is being moved in either direction on the trackway. It will be noted that the frame of this truck and the teeth thereto attached constitute together an inverted rake, adapted to act through the 95 grate-bars from the underside thereof, and to agitate the fuel consumed and other matter that may be lying upon the same. The reciprocation of the raking elements, it is 100 understood, will operate to shake down the ashes that may have accumulated on the grate-bars, so as to clear the spaces between the same, as well as to break up clinkers and remove incombustible refuse that would 105 otherwise adhere to the grates and interfere with proper combustion. The plural grates are simultaneously cleaned by the different 110 rows of raking elements, owing to their peculiar disposition on opposite sides of the intermediate supporting bars I, which is rendered possible by the surplus length of 115 the truck, hereinbefore mentioned.

As the truck is placed in the lower part 120 of the flue A, and consequently must be of less width than the centrally located grates above, the outermost raking elements cannot well be attached directly to it, and for that reason the latter-named elements, indicated by the reference characters 24^a and 25^a 125 are instead made integral parts of cross-pieces 28 and 29, carried by the nearest elements 24 and 25, pertaining to the same rows. The cross-pieces 28, 29 are made to extend outwardly a sufficient distance beyond the sides of the truck-frame to bring the outermost elements 24^a, 25^a into operative position relatively to the corresponding grate-bars, that is, those nearest to the 130 sides of the flue.

A pole or bar 31 is provided as a means to operate the aforesaid rake, in order to keep the grates clean, in the manner recited. This pole is pivotally connected, as shown, 5 to a hanger 32, depending from the forward member 19, of the truck-frame, and when at rest it may be allowed to lie across the front rod 3, of the trackway. A cross-piece 33, at the outer end of the pole, affords a convenient handle for pushing and pulling it back and forth alternately, and thereby correspondingly moving the truck and reciprocating the rake, for the purpose intended.

The said pole 31 is also provided with a hook 35, which may project downwardly from the forward portion thereof, as indicated in Fig. II. The hook 35 is adapted to take over the front rod 3, when the truck has reached the limit of its travel in the 10 rear end of the flue, and through engagement with this rod, it will operate as a stop or locking means to maintain the truck stationary, after the grate-bars have been duly cleaned. Other media, of course, could be used besides the rod 3, to co-act with the hook 35, and pole 31, in retaining the truck in any given position. In order to adjust the said rake relatively to the grates, so that the teeth thereof will project to the required 15 height above the surface of the adjoining grate-bars, the truck carrying it is raised by elevating the trackway thereunder, on the terminal supports hereinbefore described. For convenience in effecting the desired adjustment without taking the grates out of the furnace, the trackway is equipped with a movable or shiftable fulcrum, consisting preferably of a prop 37, adapted to bear upon the bottom of the flue A, and pivotally 20 connected to a transverse rod 38, that joins the rails 1 and 2 together, centrally of the trackway. The rod 38 is provided with a pair of flanges or guide-collars 39, 40, between which the head or upper end of the 25 prop is pivoted, and the lower end of the latter is formed with a foot 41, broadened so as to bear fully upon one or two of the corrugations G of the flue. Thus arranged, the prop can be used as a lifting-jack in 30 elevating the trackway, together with the truck and rake carried thereby, independently of the end supports 7 and 8. To do so, the front rod 3 is first disengaged from the pair of notches 12, which received it 35 before, in the manner indicated for instance in Fig. II, by pushing the frame like structure rearwardly inside of the flue, until the other rod 4 has slid further or deeper into the notches in the brackets 8. After this 40 has been done the forward end of the trackway is lifted high enough to cause the prop 37, which is normally inclined and inactive, to gravitate to a substantially perpendicular position, that is, until the lower extremity 45 thereof obtains a firm footing upon the cor-

rugation G of the flue, directly underneath. Next, the same forward end of the trackway is depressed to swing the rails 1 and 2, with the transverse rod 38, upon the prop or fulcrum 37, and thus cause the rear rod 4 of the trackway to become disengaged from its notches in the brackets 8, while the front rod 3 reengages the notches in the brackets 7, that is, any pair therein positioned to receive the same. This rod, like the rear one, will then sink deeper into the notches engaged thereby than it did previously. The two rods 3 & 4 are not intended to be freed simultaneously from their notches, one remaining fully in, and the other being entirely out, when the shifting takes place. At such times as the proper or desired level has been established for the trackway, the said rods occupy the positions thereof depicted by Fig. II, wherein it is shown that they reach about halfway down their respective notches. Now, it will be perceived that, by swinging or canting the trackway so as to raise and lower its opposite ends alternately in the same manner, either of the rods 3 50 and 4 can be brought into engagement with other notches 12, of the two series in the respective terminal brackets, and the relative position of the trackway, truck and rake, to the grates will be changed accordingly, all with the aid of the movable fulcrum.

It may occur that the said fulcrum will become temporarily immovable, due for instance to some ashes or clinkers impeding its capability to oscillate on the rod 38, to which it is pivotally connected. In order to counteract this impediment, a drawing means is provided between the fulcrum and the truck overlying it on the trackway. The means here referred to preferably consists of a chain 44, attached to the foot 41, of the prop 37, and thence running out of the flue forwardly. The chain 44 is furnished with a hook 45, which when not in use may be arranged to take over the outer lower edge of the furnace extension D. If and whenever the fulcrum becomes inactive, the hook 45 is caused to engage the pole-hook 35, or is otherwise anchored to the truck. Now, as the trackway carrying the fulcrum remains normally stationary, it is obvious that by drawing the truck forwardly thereon, with the chain 44 hooked to its pole or draft-bar, the pivotal connection of the fulcrum with the trackway will immediately be loosened and the fulcrum itself released for active operation.

It is to be understood that the invention herein disclosed is not limited to the precise details of construction shown and described, nor to any particular structural arrangement by which the same may be carried into practice, as numerous changes, alterations, or modifications, may be effected 130

therein without materially departing from the fundamental principle of the invention or even sacrificing any of its main advantages. The right to make all such changes, alterations, or modifications, is therefore reserved.

Having described my invention what I desire to secure by Letters Patent and claim, is:—

10. 1. In a grate cleaning appliance, a track adjustable toward or away from the grate, supporting means for said track rigidly maintaining the latter in its adjusted positions either parallel with or at an angle to the grate, a carrier mounted to travel upon the track, and rake elements mounted on said carrier adapted to project between the bars of the grate.
15. 2. In a grate cleaning appliance, a plurality of supports arranged in spaced relation beneath the grate, each of said supports having a series of spaced notches therein, a track, transverse rods associated with said track adapted to rest in said notches, a carrier on the track, and rake elements on said carrier adapted to project between the bars of the grate.
20. 3. In a grate cleaning appliance, a track disposed below the grate and adjustable toward or away from the latter, means at the ends of said track for supporting it in various positions of adjustment, a prop hingedly connected to the track beneath the same intermediate its ends, said prop being adapted to support the track free from said supporting means during adjustment thereof,

a carrier mounted on the track, and rake elements on said carrier capable of projecting between the bars of the grate.

4. In a grate cleaning appliance, a plurality of supports disposed beneath the grate, each of said supports having a series of spaced notches therein, said series extending at substantially right angles to the grate, a track, rods secured to said track adapted to rest in said notches, a carrier mounted to travel on the track, and rake elements on said carrier capable of projecting between the bars of the grate.

5. A grate cleaning appliance comprising in combination, a device for clearing the grate bar spaces operable thereunder, a track upon which said device may be moved, a set of retainers adapted to support each end of said track at different elevations relatively to the grate, and a centrally located prop capable of being positioned to raise the track and enable it to be shifted from a retainer to another in the set by rocking the track upon the prop.

6. A grate cleaning appliance comprising in combination, a cleaning device for the grate bar spaces movable beneath the same, a track for said device adjustable in height relatively to the grate, terminal retainers adapted to hold the track at different elevations, a prop pivotally attached to said track capable of raising it when moved thereunder, and flexible means adapted to form a detachable connection between the prop and the cleaning device.

WILLIAM JAMES DRAY.
